No. 657,652.

Patented Sept. 11, 1900.

C. FORTH.

CARBURETER.

(Application filed Aug. 16, 1899.)

(No Model.)

Fig. 1.

UNITED STATES PATENT OFFICE.

CHARLES FORTH, OF ELIZABETH, NEW JERSEY, ASSIGNOR TO E. P. REICHHHELM, OF BAYONNE, NEW JERSEY.

CARBURETER.

SPECIFICATION forming part of Letters Patent No. 657,652, dated September 11, 1900.

Application filed August 16, 1899. Serial No. 727,373. (No model.)

To all whom it may concern:

Be it known that I, CHARLES FORTH, a citizen of the United States, and a resident of Elizabeth, in the county of Union and State of New Jersey, have invented certain new and useful Improvements in Carbureters or Apparatus for Producing Combustible Gases or Vapors, of which the following is a specification.

10 My invention relates to generators or apparatus for producing combustible vapors or gases from petroleum or similar oils, and more particularly to that class of generators designed for employment in connection with 15 blast or other furnaces for smelting and heating metals.

The object of my invention is the production of a generator which will secure the economical and efficient production of gases or 20 vapors and which may be employed in connection with either a forced or natural draft for the attainment of either high or ordinary temperatures, at the same time insuring economy and simplicity in operation and construction, 25 effecting the perfect control and complete consumption of the vapors or gases produced, and preventing the liability to excessive carbonization and the consequent deterioration in the connected parts, as well as smoke, soot, 30 and disagreeable odors.

To these ends my invention consists in certain combinations and arrangements of parts, which will now be described with reference to the drawings and pointed out in the claims 35 at the end of the specification.

In the drawings, Figure 1 represents the generator in vertical section and shows in part the frame of the furnace. Fig. 2 is a top view of the generator. Fig. 3 is a horizontal sectional view on the line 3 3, Fig. 1, showing the construction of the valve which controls the blast.

Referring now to the figures of the drawings, in which corresponding parts are indicated by the same characters in the several views, Y represents in part the frame of the furnace (not shown) to which the generator may be detachably secured in any suitable manner. The petroleum or other oil employed to feed the generator is contained, as ordinarily, in a tank (not shown) and is fed

by gravity or in any other suitable manner through the pipe A to the generator. The outside body or shell of the generator is composed of two parts—a base-piece P, preferably 55 of cast metal, and a hood or drum O, fitting snugly therein and resting thereon. The hood O is provided at its upper extremity with one or more holes or apertures O', through which may escape the products of combustion from 60 the burner E. The vaporizing-chamber is preferably formed as a pipe D, suitably supported within the generator-chamber and fixed in position in the cylindrical sleeve D' of the base-piece P and passing through the 65 top of the hood or drum O. Surrounding the tube D near its base and attached to the base-piece P is the annular burner E, at which point the flame is produced for vaporizing the oil in the tube D. The annular burner 70 E is provided with an integral ring or depending piece E', also connected to the base-piece P, the object of this annular extension being to provide a resting-place for the wood-alcohol or other inflammable material which 75 may be employed to initiate the operation of vaporizing in the tube D. The vapor formed in the tube D is permitted to pass through the regulated and invariable opening H into the mixing-chamber G, situated above the 80 generator proper. This opening or outlet H is controlled by the needle-valve H', which serves the double purpose, first, of closing the opening H to shut off the vapor when the furnace is not being used, and, second, when operated of clearing and keeping the opening H free from all obstruction. Also passing through the casing of the generator-chamber and into the mixing-chamber G is a blast-pipe F, through which is forced air under 85 pressure in the customary manner. This blast-pipe F may be supported in any desired manner and is shown in the drawings as passing through a bracket or projecting piece F', attached to the base-piece P. Also passing 90 from the mixing-chamber G into the generator-casing is the pipe or conduit I, designed to supply vapor from the mixing-chamber G to the burner E for the maintenance of the vaporizing heat in the ordinary operation of 95 the apparatus. This pipe I may be supported in any desired manner and is shown in the 100

drawings as supported by a bracket or projecting piece I', attached to the base-piece P, through which, as also through the ring E', the pipe I passes in order to convey the vapor 5 to and beneath the burner E.

The mixing-chamber G is provided at one end with an outlet, such as the pipe or coupling J, through which the mixed vapor is carried by the blast from the pipe F to the several places of combustion in the furnace where it is employed. The coupling or pipe J is provided with a stop-cock or valve J'. The mixing-chamber G is provided with a second opening closed by the plug or stop x, which 15 permits the mixing-chamber to be opened to the atmosphere in the event of the discontinuance of the blast through the pipe F, or if it be intended to employ in the furnace a less degree of heat—as, for instance, when 20 the smelting has been completed by means of the blast and it is desired simply to maintain the metal in molten condition.

The supply of oil through the pipe A to the tube D is governed by the valve B, which may 25 be of any desired form of construction and is operated by the handle C. The supply of the air-blast through the pipe F is determined by the sliding valve M, (see Fig. 3,) which moves in the slide K, attached to the pipe F, and is 30 provided with an aperture M' of any approved form in such manner that the supply of air therethrough may be governed at will. The sliding valve-piece M is attached by the link L to the operating-handle C of the valve 35 B. Arranged in proximity to the handle C is a scale, attached to the frame of the furnace in such manner that the regulation of the oil-supply and the air-blast may be readily and accurately secured by a single movement of the handle C.

The operation of my improved apparatus may now be readily understood. The oil passes from its receptacle through the pipe A into the generating-chamber D, wherein it 45 is converted into vapor in the first instance at the initiation of the operation by the temporary or starting flame produced upon the ring or flange E and afterward during the continued operation of the apparatus by the 50 heat of the flame from the burner E, to which vapor is fed through the pipe I from the mixing-chamber G. The outlet or opening H is opened by the operation of the needle-valve H', and the vapor is thereby permitted to pass 55 into the mixing-chamber G. This passage of the vapor through the outlet H is facilitated and caused by the action of the air-blast, which, passing from the pipe F into the mixing-chamber G, not only serves by its suction 60 to cause entrance into the mixing-chamber of a uniform and steady supply of the vaporized oil from the tube D, but after thoroughly mixing with it in the mixing-chamber carries it to the several points of combustion in the 65 furnace and effects the forced blast therein. The pressure of the air-blast in the chamber G also causes a portion of the mixed vapor

to pass through the tube I to the bottom of the generator and feeds it to the burner E, where it is utilized in a flame of the desired 70 intensity to continue the process of vaporization in the tube D. It will be noted also that the location of the blast-pipe F and the tube I within the exterior casing of the generator, whereby they are both subjected to the continued heat from the burner E, has the effect 75 of heating the air-blast in the pipe F to a considerable extent before it enters the mixing-chamber G and of maintaining the secondary supply of mixed vapor in the tube I in 80 its proper condition and of preventing its condensation therein.

This arrangement of apparatus as described I have found to be most efficient in practice, and I have been able to secure in 85 its employment such high degrees of temperature as to effect the reduction of the most refractory substance in the furnace. By the construction previously indicated I am also enabled to use this generator without forced draft and with simply the ordinary pressure of the atmosphere by simply discontinuing the blast through the pipe F and removing the plug or stop x from the end of the mixing-chamber. This feature I have 95 found to be of great advantage where it is desired to produce only an ordinary degree of heat—as, for instance, to maintain the metals in molten condition after their reduction has been effected by the employment of the 100 blast. I also lay great stress upon the ability to accurately and readily govern both the supply of oil to the vaporizer and the force of the blast to the mixing-chamber by a single movement of the handle C in connection 105 with the scale. It will be seen that indirectly this movement of the handle also governs the supply of vapor through the pipe I to the burner E, as when the amount of mixed vapor and the force of the blast in the mixing-chamber are increased or diminished the supply of vapor through the pipe I to the burner E will 110 be proportionately increased or diminished. It therefore follows that by a proper adjustment of the connected parts the amount of 115 oil supplied to the vaporizer, the force of the blast to the mixing-chamber, and the intensity of the vaporizing-flame will always exactly correspond. In other words, by this means of adjustment the supply of the several elements is so proportioned as to secure 120 perfect combustion always, the supply of the oil to be vaporized being always in exact accord with the force of the blast and with the intensity of the vaporizing-flame. This construction is one of great importance, as the even and properly-proportioned combustion 125 prevents the production of smoke, soot, and annoying vapors, as well as injurious deposits, which in ordinary practice affect the utility 130 of the several parts and necessitate their frequent renewal.

The apparatus as herein presented, and as demonstrated by extensive employment, is

well adapted not only for securing by the aid of the blast the highest temperatures required in metallurgy, but also to a vast variety of uses in connection with the ordinary atmos-

pheric pressure.

A form of gas-furnace in connection with which my improved generating apparatus may be advantageously employed is well illustrated in the United States Patent to E. P.

10 Reichhelm, No. 405,051, June 11, 1889. In this form of furnace is provided a plurality of burners, and, as will be obvious, the force of the blast will be sufficient and necessary to carry the mixed vapor to the several places 15 of combustion. I am well aware, as illustrated in the said patent, that it is old in the art to employ a blast in such a furnace, the force of the blast being relied on to cause the mixing of the gas with the blast and the conveyance 20 of the mixed vapor to the several places of combustion. It is to be noted, however, that the gas employed in such a furnace is obtained from an ordinary source of supply. I believe myself to be the first to employ 25 a blast in connection with a generating or vaporizing apparatus provided with suitable means for regulating and securing a mixed vapor in any desired proportion, which is carried by the force of the blast to the several 30 points of combustion. It will be seen that by the employment of my improved apparatus I am enabled to dispense with the blasts of the furnace proper and that the apparatus, being independent of the furnace, 35 may be employed in connection with any furnace and in any desired manner.

I have herein presented an approved and desirable form of the embodiment of my improved devices; but it will be understood that 40 many variations may be made therein, both in the character of the elements and in their mode of employment, without departing from the spirit of my invention.

Having thus described my invention, what 45 I desire to secure by Letters Patent of the United States and claim is as follows:

1. The combination of the closed mixing-chamber provided with a suitable outlet, a vaporizing-chamber connected therewith, and 50 a blast-pipe also connected therewith, in such manner that the force of the blast continuously causes its admixture with the vapor, and the carriage of the mixed vapor to the several places of combustion, together with suitable means for heating the air in the blast-pipe and producing the vapor in the vaporizing-chamber.

2. The combination of the closed mixing-chamber provided with a suitable outlet, a 55 vaporizing-chamber connected therewith, and a blast-pipe also connected therewith, in such manner that the force of the blast continuously causes its admixture with the vapor, and the carriage of the mixed vapor to the several 60 places of combustion, suitable means for controlling the force of the blast and the supply of vapor so that they may be mixed in the

proper and desired proportions, together with suitable means for heating the air in the blast-pipe and producing the vapor in the vaporizing-chamber.

3. The combination of the closed mixing-chamber provided with a suitable outlet, a vaporizing-chamber connected therewith, a blast-pipe also connected therewith, a burner 75 arranged to heat the air in the blast-pipe and to produce the vapor in the vaporizing-chamber, and a connection from the mixing-chamber to the burner, which connection is also subjected to the heat from the burner, the whole arranged so that the force of the blast continuously causes the injection of the vapor, the admixture of the vapor with the blast, and the division of the mixed vapor into two parts, a portion of which is forced under blast to the 80 several places of combustion, and the remaining portion to the heating and vaporizing burner.

4. In an apparatus for producing combustible vapors, the closed mixing-chamber provided with a suitable outlet, and a heating or vaporizing chamber connected therewith, the said mixing-chamber being provided with two inlets, through one of which when desired a blast may be admitted to the mixing-chamber, 90 and through the other of which air under the ordinary atmospheric pressure may be admitted when the blast is discontinued.

5. In an apparatus for continuously producing combustible vapors, the combination 100 of the closed mixing-chambers provided with a suitable outlet, a vaporizing-chamber connected therewith, a blast-pipe also connected therewith, means to supply the fluid to the vaporizing-chamber, and suitable valves for 105 controlling respectively the supply of fluid to the vaporizing-chamber, and the intensity of the blast to the mixing-chamber, the said valves being connected in such manner that they may be controlled simultaneously, together with suitable means for heating the air in the blast-pipe and producing the vapor in the vaporizing-chamber.

6. In an apparatus for continuously producing combustible vapors, the combination 115 of the closed mixing-chamber provided with a suitable outlet, a vaporizing-chamber connected therewith, means to supply the fluid to the vaporizing-chamber, a blast-pipe connected to the mixing-chamber, a burner to 120 heat the air in the blast-pipe and to produce the vapor in the vaporizing-chamber, means for supplying vapor from the mixing-chamber to the burner, which means are also subjected to the heat from the burner, together 125 with valves suitably connected so that their simultaneous operation controls the supply of fluid to the vaporizing-chamber, the intensity of the blast to the mixing-chamber, and the supply of vapor to the burner.

7. In an apparatus for producing combustible vapors, the combination with the exterior casing of the generator, and the burner contained therein, of the blast-pipe, and the pipe

designed to supply vapor to the burner, both of the said pipes passing through the generator-casing and being thereby subjected to the heat from the burner together with means for supplying vapor to the generator.

8. In an apparatus for producing combustible vapors, the combination with the exterior casing of the generator, and the burner contained therein, of a blast-pipe, and the vaporizing-chamber; both of which are contained within the generator-casing and are thereby subjected to the heat from the burner.

9. In an apparatus for producing combustible vapors, the combination of the blast-pipe

and the vaporizing-chamber, with a single burner arranged to heat the air in the blast-pipe and to produce the vapor in the vaporizing-chamber.

In testimony whereof I have signed my name to this specification, at the city of New York, in the county of New York and State of New York, this 10th day of August, A. D. 1899, in the presence of two subscribing witnesses.

CHARLES FORTH.

Witnesses:

JAMES P. J. MORRIS,
JOHN SMITH.
